UNITED STATES PATENT OFFICE

GEORGE A. McBRIDE, OF MUSKOGEE, OKLAHOMA, ASSIGNOR TO THE PURE OIL COMPANY, OF CHICAGO, ILLINOIS, A CORPORATION OF OHIO

CENTRIFUGAL DYE MIXER

Application filed June 11, 1928. Serial No. 284,343.

This invention relates to improvements in centrifugal dye mixers and has for one of its outstanding objects the provision of apparatus for intimately bringing a quantity of liquid into contact with a body of dye material for the purpose of producing a desired color effect or appearance in the liquid, to utilize to the greatest degree the color imparting properties of the dye and particularly to prevent waste of the dye material.

The invention also has for an additional object to provide a dye mixer particularly useful in the coloring of gasolines or motor fuels, and to permit this to be carried out in an economical, effective and labor saving manner.

For a further understanding of the invention reference is to be had to the following description and the accompanying drawings, wherein:

Figure 1 is a horizontal sectional view taken through a centrifugal dye mixer formed in accordance with the present invention, the plane of the figure being indicated by the line 1—1 of Figure 2,

Figure 2 is a vertical sectional view taken through the dye mixer on the plane indicated by the line 2—2 of Figure 1,

Figure 3 is a transverse vertical sectional view taken through the dye mixer on the line 3—3 of Figure 2,

Figure 4 is a plan view of the bottom of the dye cage,

Figure 5 is an enlarged detail vertical sectional view on the line 5—5 of Figure 4,

Figure 6 is a plan view of the removable closure plate carried by the bottom of the dye cage,

Figure 7 is an edge view of said plate.

Many motor fuels now found on the market are artificially colored for the purpose of distinguishing such fuels and to enable them to be readily recognized by the purchasing public. The present invention provides simple, effective and positive means adapted for the purpose of economically and positively dyeing or coloring such a motor fuel and to permit this to be done with but minimum loss in time, materials and labor.

The improved dye mixer comprising the

present invention consists of a horizontally extending pipe section 1, which has its intermediate portion vertically flattened as indicated at 2 so as to produce a narrow elongated vertical passage 3. One of the walls 55 of this passage is cut away as at 4 for the reception of the vertically extending casing 5 of the mixer. This casing is preferably welded or otherwise rigidly secured as at 6 to the marginal portion of the opening 4. Similarly the inner part of the casing 5 is cut away and provided with an opening 7 on one side so as to register with the opening provided in the passage 3. By this construction the casing 5 and the pipe section 1 are unitarily and stationarily combined. The opposite ends of the pipe section 1 are threaded as at 8 for the reception of internally threaded coupling sleeves 9, which position and operatively connect the mixer in a pipe line 10 65 through which a liquid motor fuel is forced.

In order to dye or color the liquid motor fuel during its passage through the pipe line 10 and particularly the restricted passage 3, there is arranged for rotary movement about a vertical axis with the casing 5 a rotary dye cage and impeller units 11 and 12 respectively. The impeller unit consists of a circular lower plate 13, having its axial portion provided with a threaded opening 80 adapted for the reception of a threaded end of a journaled stud 14. This stud is received within a socket provided centrally within a bushing 15 formed in connection with the lower circular head 16 of the casing 5.

The upper portion of the impeller unit includes an annulus 17, which is united with the outer peripheral portion of the plate 13 by means of a plurality of vertically extending circularly spaced blades 18. The plate 13 and the annulus 17 are further united by vertically extending tie rods 19. It will be observed that the blades 18 enter the restricted passage 3 and the pipe section 1, so that as the fluid under pressure passes through said pipe section it will contact with the blades 18 and effect the rotation of the impeller unit about the axis of the stud 14.

Removably positioned within the impeller unit is the dye cage 11. This dye cage con-

sists of a circular head 20 arranged in the upper portion of the dye cage, and which head is provided with a marginal flange arranged to be received within a circular recess formed in the annulus 17. Depending from the head 20 are tie rods 21, which serve to unite the head 20 with a ring 22 situated in the lower part of the dye cage. The vertical walls of the dye cage are provided with a fine mesh iron screen, as indicated at 23, which screen permits of the passage to a limited extent of the liquid fuel into the dye cage or container. The head 20 is provided centrally with an upstanding stud 24, arranged in registration with the stud 14. The stud 24 is rotatably received within a socket provided in a bushing 25, which is threaded into a removable cover plate 26 arranged on the top of the casing 5.

Pivottally connected to depending bars 27, carried rigidly and exteriorly by the lower part of the casing 5, is a yoke frame 28. This frame normally has its upper horizontally extending bar provided with a threaded opening for the reception of a vertically extending screw 29, which carries at its upper end a transversely extending operating rod 30. Normally the lower end of the screw 29, as shown in Figure 2, engages with a seat provided in the upper surface of the bushing 25. However, when it is necessary from time to time to replenish the dye material, which is deposited in the cage 20, it is necessary merely to elevate the screw 29 so as to remove from engagement with the bushing 25. This permits the frame 28 to be rocked about its pivotal mounting and moved to a position clear of the cover plate 26. The cover plate may then be removed from the top of the casing 5 and the cage unit 11 withdrawn from the impeller unit or withdrawn with the impeller unit from the cage.

The bottom ring 22 of the dye cage includes a horizontally extending segmental flange or lip 31, which acts as a support for a removable disc-like plate 32, which is carried in the bottom of the cage unit. The flange or lip 31 is provided with double surfaces registering with corresponding surfaces formed on the peripheral portion of the plate 32, so that when said plate occupies a position of closure within the ring 22, it is secured against accidental displacement.

In operation, a predetermined amount of an oil soluble aniline dye is placed in the dye cage when the latter is removed from the cage 5 and also by removing the plate 32. After the cage has been filled with a quantity of this dye, or equivalent material, the plate 32 is then again inserted in its position of closure. The dye cage is then placed within the impeller and the stud 14 of said impeller is placed for rotation within the bushing 15 provided in the bottom of the casing 5. The cover plate 26 at the casing 5 is then posi-

tioned on the top of the casing, and the frame 28 is swung to a position permitting of registration of its screw 29 with the top of the bushing 25. By tightening the screw 29 the cover plate is maintained in firm sealed engagement with the upper edges of the casing 5 preventing loss of liquid materials. The valves (not shown) which permit of the flow of a liquid fuel through the pipe line 10 are then opened so that such fuel may pass through the pipe section 1 and more particularly the passage 3. This results in causing the rotation of the dye cage and impeller so that all portions of the dye in the cage are subjected to the washing effect of the incoming motor fuel, thereby accomplishing the purpose of the apparatus which is to insure complete solubility. If desired, the apparatus may be screwed or otherwise secured on to the standpipe at the loading rack which leads to a tank car. Another standpipe is secured on to the bottom of the apparatus leading to the bottom of the tank car. With this arrangement complete solubility is effected with a minimum evaporation loss of the gasoline or other hydrocarbon product to be dyed.

The method herein disclosed is claimed in my co-pending application Serial No. 433,720, filed March 6, 1930.

What is claimed is:

1. A dye mixer of the character set forth comprising a liquid circulating conduit having its intermediate portion formed to present a vertically elongated relatively narrow liquid passage, a receptacle formed with one side of the intermediate portion of said conduit with the interior of said receptacle in open communication with said passage, an impeller formed to include a plurality of vertically extending plates rotatably mounted within said receptacle and so disposed that the plates thereof project into said passage whereby upon the flow of liquid through said passage said impeller is rotated, a dye cage formed to include a perforated outer wall removably mounted in connection with said impeller, means admitting of rotation in unison on the part of said impeller and dye cage.

2. A dye mixer comprising a casing formed to include communicating liquid passages and a dye cage compartment, said liquid passages at the point of communication with said compartment being of an elongated restricted form, a perforate dye cage rotatably mounted within said compartment, said dye cage being adapted to receive solid dye materials, radial vanes formed upon the peripheral portion of said cage and arranged to project upon the rotation of the cage into the restricted portion of said liquid passage whereby during the flow of liquid through said passage said cage is rotated, and axially disposed bearings formed with said cage for effecting

its rotatable support within its compartment.

3. In apparatus for imparting soluble substances to flowing streams of liquid, a casing formed to include a liquid passage having ends of circular cross-sectional formation and adapted for connection with standard pipe members through which a flowing stream of liquid is adapted to be passed, the intermediate portion of said passage being provided with a restricted throat having a cross-sectional formation abnormal to that of the ends of said passage, said throat possessing a materially greater height than width, the casing being provided with a compartment arranged laterally of and in open communication with one side of said throat, a perforate container for powdered materials soluble in the liquids passed through said passage mounted for rotation about a fixed vertical axis in said compartment, and radial vanes projecting from the peripheral portion of said container and responsive to the flow of liquid through said throat to effect the rotation of said container, said radial vanes extending substantially throughout the height of said throat.

4. In apparatus for imparting soluble bodies to liquids, a conduit adapted for the passage of a liquid flow stream, the ends of said conduit being substantially circular in cross section while its intermediate portion is distorted to produce a throat having a greater height than width, a casing formed with one of the side walls of said throat, said casing and adjoining side wall being provided with registering openings providing for open communication between the interior of said casing and said throat, a container for powdered soluble substances rotatably mounted in said casing, said container being provided with perforate walls, and vertical longitudinally disposed vanes rigidly connected with the peripheral portion of said container and extending into the moving stream of liquid flowing through said throat, whereby to effect the rotation of said container by the movement of the liquid flow stream.

5. In apparatus for imparting soluble bodies to liquids, a conduit through which a liquid is adapted to be passed, said conduit having the intermediate portion thereof flattened to provide a vertically elongated relatively narrow throat, a casing formed with the intermediate portion of said conduit, a container rotatably mounted in said casing, and vertical longitudinally extending vanes rigidly connected with the peripheral portion of said container and extending radially from the axis of rotation of said container into the moving stream of liquid passing through said conduit, whereby to effect the rotation of said container by the movement of said liquid through said conduit.

6. Apparatus for imparting soluble substances to flowing streams of liquid, a casing

formed at one side with a conduit for the passage of liquid in a confined flow stream, said conduit having an intermediate portion thereof distorted to produce a vertically elongated relatively narrow throat, an impeller frame 70 rotatably mounted in said casing about a vertical axis, a plurality of vertically extending vanes carried by the peripheral portion of said impeller frame and arranged to project into said throat for contact with the 75 liquid passing therethrough whereby the flow of said liquid effects the rotation of said frame, and a perforate container for substances soluble in said liquid removably positioned in the impeller frame.

In testimony whereof I affix my signature.
